UNITED STATES PATENT OFFICE.

GEORG WAZLAVIK, OF MILWAUKEE, WISCONSIN.

CABINET.

SPECIFICATION forming part of Letters Patent No. 772,982, dated October 25, 1904.

Application filed April 30, 1903. Serial No. 154,928. (No model.)

To all whom it may concern:

Be it known that I, GEORG WAZLAVIK, residing at Milwaukee, in the county of Milwaukee and State of Wisconsin, have invented a new and useful Improvement in Cabinets, of which the following is a description, reference being had to the accompanying drawings, which are a part of this specification.

The object of this invention is to provide a novel cabinet which in small size is intended and adapted for the amusement of children, especially little girls. The invention is, however, not to be understood to be limited exclusively to a toy construction, as in a larger size the cabinet might be employed as household furniture for the use of adults.

The novel features of the cabinet relate chiefly to the inclosing case, including its flexible sliding doors, to the interior arrangement of the cabinet and its folding and sliding bedstead or frame, and minor features incidental thereto.

The invention consists of the cabinet, its parts and their combinations, as herein described and claimed, or the equivalents thereof.

In the drawings, Figure 1 is a front elevation of the improved cabinet. Fig. 2 is a vertical section centrally of the cabinet at a right angle to the front view shown in Fig. 1. Fig. 3 is a transverse section of the cabinet on line 3 3 of Fig. 2 looking downwardly. Fig. 4 is a view of the bedstead forming a part of the cabinet looking at it from the rear as it is folded up in Fig. 2. Fig. 5 is a front view of a fragment of the cabinet, the case being open and the bedstead being thrown down and opened out in position for use. Fig. 6 is a transverse section horizontally of the cabinet, the bedstead being pulled out at the front and opened out for use, as shown in Fig. 5. Fig. 7 is a detail of the door-fastening device.

Referring to the drawings, my improved cabinet includes a case 1 in box-like form, preferably made chiefly of wood, the case including a back 2, sides 3 3, a top 4, a bottom 5, and front side rails 6 6. Also a drawer 7 is arranged to slide into the case below the bottom 5, and doors 8 8 are provided for closing the otherwise open front of the cabinet above the floor 5.

The two rigid doors 8 8, each as high and the two together as wide as the opening in the front of the cabinet which they are adapted to close, are provided with glazed openings 9 9 and at their side edges are hinged to the first 55 bar 10 of a series of bars succeeding and secured thereto by a hinge or flexible attachment, preferably consisting of a piece of cloth or fabric 12, glued or cemented to each of the series of bars. These bars are as long as the 60 height of the doors and are arranged adjacent to each other successively in vertical position, and these bars and the doors themselves connected thereto rest and travel on the floor 5, being guided in their paths of travel by the sides 65 3 3 of the cabinet, an outer guard 13, one at the bottom and one at the top of the cabinet, and an inner guard 14, one at the bottom and one at the top of the cabinet, the several guards, in connection with the sides of the cabinet 70 3 3, forming grooves on the bottom and at the top of the cabinet in which the doors and the flexible door-supports (made up of the bars 11 11 and the connecting fabric 12) are retained and travel. It will be understood that 75 when the doors 8 8, each of which is of considerable size, are to be used to close the front of the cabinet the doors with the flexible supports are drawn out at the front, and the doors are then swung toward each other in 80 the manner shown in Fig. 3, thereby closing the cabinet, and that when the cabinet is opened the doors are swung open, and then the flexible supports and the doors are pushed into the cabinet rearwardly, taking the positions shown in Fig. 6. For securing the doors in closed position, as shown in Figs. 1, 2, and 3, one of the doors is fastened by a spring-latch 15, secured to the floor of the cabinet and arranged to engage a catch 16, fixed on 90 the door. The other door is provided with a swinging latch 17, pivoted on the door near its edge and arranged when the doors are in closed position to engage by being swung thereto a pin-catch 18, fixed in the other door. 95 The pivot of the swinging latch 17 terminates in an outwardly-projecting faced arbor on which a key 19 fits removably, which key is adapted to swing the latch 17 into or out of engagement with the pin-catch 18. 100

Within the cabinet and as a part thereof a bedstead or crib is provided, which consists of the bottom frame 20, hinged at one side onto the supporting-blocks 21 21, which are 5 dovetailed and slidable forward and back in undercut grooves 22 22 in the guard-piece 14, forming a part of the bottom of the cabinet. An open-work footboard 23 and open-work side boards 24 24 are hinged to rails 30 30, 10 faced on the bottom frame, and are adapted to swing to vertical positions thereon, and the footboard is arranged to be secured to the side boards releasably by hooks 25 25, hinged on the footboard and adapted to engage eyes 15 fixed in the ends of the side boards, whereby the footboard and the side boards are locked to each other in upright positions. At the head ends the side boards are provided with extensions 26 26, hinged to the side boards 20 and adapted to be swung to extending positions when in use and to be folded down onto the side boards when the side boards are first folded down onto the end boards. An open-work headboard 27 is hinged to the bottom frame 25 20 and is so mounted that it is capable of being folded down onto the bottom frame as well as the footboard and to be swung upwardly into vertical position, to be there secured to the side boards or over farther into 30 an inclined position, as shown in Figs. 5 and 6, in which position it is adapted to be secured to the extension side boards 26 26 by means of hooks 28, hinged on the headboard and adapted to engage eyes fixed in the 35 tension side frames. When opened up into position for use, the crib or bedstead has upright side boards and a footboard and an inclined headboard, as will be understood from Figs. 5 and 6. A folding leg 29 is hinged 40 on the bottom frame 20 at its outer edge and is adapted to stand on the floor when the crib is pulled out for use and to fold against the under side of the bottom frame when the crib or bedstead is pushed back into the cabinet 45 and is upturned against the rear, as shown in Fig. 2.

When this cabinet is constructed in small size, it is adapted for use as a doll's house, and when it is to be closed up one or more dolls may be placed in the cabinet and inclosed behind 50 the glazed doors, as shown in Fig. 1, and when the cabinet is opened the crib may be drawn out and the dolls can be placed on a bed made in the crib.

An ornamental front 31 of any preferred design 55 may be placed on the top of the cabinet net in the manner shown in Figs. 1 and 2.

What I claim as my invention is—

In combination, an upright cabinet having a floor a top and a back leaving the front 60 open, ways on the inside of the cabinet on the floor and the top at the sides and continuously around at the back, laterally-flexible door-supports extending from the bottom to the top of the cabinet on the inside and supported and traveling in the ways at the sides and back of the cabinet but together of less length than the length of the ways, a crib-like apparatus mounted on blocks to swing down and up, ways on the floor of the cabinet extending from the front substantially to the rear of the cabinet, blocks slidable in said ways on which said crib is mounted, the construction being such that when the flexible door-supports are withdrawn from the ways 75 therefor at the back said blocks can be pushed back to the rear of the cabinet and the crib can be folded up against the back of the cabinet between and in the place of said withdrawn flexible supports, and when the blocks 80 and crib are folded forward the flexible supports can be pushed back into the ways at the rear of the cabinet withdrawing the doors from the front to the sides of the cabinet and the crib can then be unfolded across 85 and in front of the door-opening of the cabinet.

In testimony whereof I affix my signature in presence of two witnesses.

GEORG WAZLAVIK.
